UNITED STATES PATENT OFFICE.

JAMES POWERS, OF PLATTVILLE, ILLINOIS, ASSIGNOR OF TWO-THIRDS TO JOHN FINDLEY AND GAMALIEL BELFIELD, OF SAME PLACE.

DESIGN FOR A FORK-SOCKET.

SPECIFICATION forming part of Design No. 32,364, dated March 20, 1900.

Application filed December 30, 1899. Serial No. 742,176. Term of patent 7 years.

To all whom it may concern:

Be it known that I, JAMES POWERS, a citizen of the United States, residing at Plattsburgh, in the county of Kendall and State of Illinois, have invented a new and useful Design for a Fork-Socket, of which the following is a specification.

The essential feature of my design resides in the peculiar shape and configuration of the article, as shown in the drawing forming a part of this application, and which is a perspective view of the socket constructed in accordance with my design.

The socket A is essentially cylindrical in shape and has a flaring mouth B. At the base

of the socket is a tapering web C, to which is joined a square plate D, having circular openings E. A series of longitudinal slots F are produced in the socket, and surrounding the said socket adjacent to the upper end is a band G, the ends of which diverge, as shown at II.

Having thus fully described my invention, what I claim as new, and desire to secure by Letters Patent of the United States, is—

The design for a fork-socket, substantially as herein shown and described.

JAMES POWERS.
